UNITED STATES PATENT OFFICE.

RICHARD LAVERY, OF BOSTON, MASSACHUSETTS.

STEAM-BOILER FURNACE.

SPECIFICATION forming part of Letters Patent No. 322,298, dated July 14, 1885.

Application filed December 22, 1884. (No model.)

To all whom it may concern:

Be it known that I, RICHARD LAVERY, a citizen of the United States, residing at Boston, in the county of Suffolk and State of Massachusetts, have invented certain new and useful Improvements in Marine and other Steam-Boiler Furnaces, of which the following is a specification.

In the ordinary construction of marine or other boilers the fire-bridge linings are usually built up of fire-brick, which very soon becomes destroyed in consequence of the great heat and the action of the firing-tools used in cleaning out the furnaces and breaking off the clinkers, &c., resulting in great waste of fuel and expensive repairs. The linings of the furnace are usually made of brick, and being unsupported soon go to pieces.

It is the object of my invention to obviate these defects; and to that end the invention consists in constructing the linings of the furnace and fire-bridge in sections composed of metallic boxed frames, into which are partially inclosed and held securely fire-brick or other suitable non-combustible material. The said boxed frames and non-combustible material are bolted separately to the front plate of the furnace to form the front lining of the furnace and to a base-plate to form the fire-bridge and the lining of the same, so that each or any section can be removed for renewal independently of the others, whereby in case any portion of the furnace or fire-bridge lining becomes damaged or destroyed a new section can be expeditiously put in place. In the portion of the furnace-front comprising the aperture for firing, the boxed frames are constructed to perform the dual office of furnace-lining and mouth-piece, and are shown in the drawings as applied to the furnace of a typical marine-boiler now in general use to supply compound engines with steam.

Referring to accompanying drawings, which form part of this specification, Figure 1 represents a longitudinal vertical section through the furnace of a boiler embodying my invention. Fig. 2 is a front view of same. Fig. 3 is a transverse vertical section taken on line x-x Fig. 1, showing the inner side of the furnace-front as viewed from the rear of the furnace,

and also the aperture for firing. Fig. 4 is a transverse vertical section taken on line y-y of Fig. 1, showing the front of the fire-bridge and base-plate. Fig. 5 is a perspective view of one of the metallic upper boxed frames or sections of furnace-front lining with the non-combustible material removed. This section is one of the number forming the mouth of furnace or aperture for firing. Fig. 6 is a perspective view of one of the metallic sections of the fire-bridge lining and bridge.

A represents a portion of a marine-boiler, of which B is the furnace, B' the ash-pit, C the front plate, and D the door. E is a base or dead-plate of metal, extending across the front of the furnace on a level with the grate-bars, and is secured to the front plate, C, by means of bolts and nuts e.

Resting upon the dead-plate E are the first of a series of metallic boxed frames (into which are incased the non-combustible material) constituting the sections F F' F'', that form the lining and also the aperture or mouth of the furnace. These sections are made of such form as to securely hold a filling of fire-brick, G, or other non-combustible substance, and at the same time expose as little as possible of the metal to the action of the fire. Each of these sections is secured to the front plate, C, by means of a bolt and nut, f, so that should one section become damaged by unscrewing the nut from the bolt of said section the section can be removed and replaced by a new one without disturbing the others.

In the drawings I have shown the furnace-lining and aperture or mouth as being composed of the dead-plate E and six frames or sections, F F' F'' F'' F''; but the number and form of the sections may be varied as required. At the rear of the furnace I place a bridge-wall composed of a base-plate, H, of metal, made to fit the lower part of the furnace or ash-pit B'. This base-plate is supported and held in position by means of chains h h, secured to the sides of the furnace.

I prefer to make the base-plate H of T form and strengthen it with ribs, as shown.

To the top of the base-plate H, I secure a series of frames or sections, I, by means of bolts and nuts i. These frames or sections I

prefer to make of the form shown in Fig. 6, so that when secured in position they will form between them chambers or spaces, into which are fitted fire-brick K, or other suitable 5 non-combustible material, thus forming a fire-bridge lining and bridge that will expose very little of the metal work to the action of the heat, and which at the same time can be readily repaired should any of the sections become 10 damaged.

I prefer to make the fire-brick blocks G and K so that their surfaces will stand slightly beyond the edges of the frames that hold them in position. By this arrangement I preserve 15 the metal work from a very large amount of the action of the fire, thus causing them to last much longer than if not so protected.

It will be seen by the arrangements herein described that every or any part of the furnace 20 and fire-bridge linings and fire-bridge can be readily removed and replaced by a corresponding new portion, and thereby save time and expense.

I do not claim a mouth-piece composed of 25 metal plates resting upon and interlocking with each other in flanged tongues and grooves for the purpose of protecting the brick walls of the furnace from the wearing action of the tools while firing, as this has been used before; 30 but

I do claim and desire to secure by Letters Patent—

1. The combination of the bridge-wall or base-plate H and the removable metallic independent boxed frames or sections I, as shown 35 and described.

2. The combination of a furnace-lining and the aperture or mouth composed of boxed frames or sections (into which are partially embedded fire-brick or other non-combustible 40 material) that can be separately detached and replaced by new ones, substantially as shown and specified.

3. In a marine or other boiler furnace, the combination of the front plate, C, the sections F F' F'', the fire-brick or other non-combustible material G, and the dead-plate E, substantially as and for the purpose shown and specified. 45

4. The combination of the sections I of the fire-bridge and the filling of fire-brick or other non-combustible material, substantially as set forth. 50

5. In a marine or other boiler furnace, the independent boxed frames or sections F F' F'', 55 holding fire-brick or other suitable non-combustible material, said sections being secured to the front plate, C, by means of bolts and nuts, and when in position serving in the dual capacity of furnace-lining and aperture or 60 mouth for admission to the interior of the furnace, substantially as and for the purpose specified.

In testimony whereof I have signed my name to this specification in the presence of two sub- 65 scribing witnesses.

RICHARD LAVERY.
